CLAIM

We claim the ornamental design for the azimuth-elevation gimbal antenna, as shown and described.

DESCRIPTION

FIG. 1 is a perspective view of our new design for an azimuth-elevation gimbal antenna, shown in full line; and, FIG. 2 is a reverse perspective view thereof.

The broken lines in the Figures are for illustrative purposes only and form no part of the claimed design.

The surfaces of the article not shown in the drawing or described in the specification form no part of the claimed design.
